UNITED STATES PATENT OFFICE.

FREDERICK G. GRUEN, OF CINCINNATI, OHIO, ASSIGNOR TO THE D. GRUEN SONS & COMPANY, OF CINCINNATI, OHIO, A CORPORATION OF OHIO.

DESIGN FOR A WATCHCASE AND DIAL.

51,439.

Specification for Design.

Patented Oct. 30, 1917.

Application filed August 9, 1917. Serial No. 185,360. Term of patent 7 years.

To all whom it may concern:

Be it known that I, FREDERICK G. GRUEN, a citizen of the United States of America, and resident of Cincinnati, in the county of Hamilton and State of Ohio, have invented a new, original, and ornamental Design for a Watchcase and Dial, of which the following is a specification.

My design relates to the ornamentation of a front of an open face watchcase and dial.

The figure is a front elevation of a watchcase and dial embodying my invention.

A design of my invention comprises a circular ornamental wreath embossed upon the front of the watch casing adjacent to its

periphery, the wreath substantially filling in the space of the band, a second circular band adjacent to the inner edge of said band, a circle of ornamentation within said second band, and a scroll-like ornamentation upon the center of the dial-plate.

I claim;

The ornamental design for a watchcase and dial as shown and described.

In testimony whereof, I have hereunto subscribed my name this 7th day of August, 1917.

FREDERICK G. GRUEN.
